UNITED STATES PATENT OFFICE.

THEODORE A. PARMENTER, OF RACINE, WISCONSIN.

VALVE-GRINDING TOOL AND THE LIKE.

1,425,684.

Specification of Letters Patent. Patented Aug. 15, 1922.

Application filed April 8, 1921. Serial No. 459,700.

To all whom it may concern:

Be it known that I, THEODORE A. PARMENTER, a citizen of the United States of America, and resident of Racine, county of Racine, State of Wisconsin, have invented 5 certain new and useful Improvements in and Relating to Valve-Grinding Tools and the like, of which the following is a specification.

10 This invention relates to certain improvements in valve grinding tools and the like; and the nature and objects of the invention will be readily understood by those skilled in the art in the light of the following explanation of the accompanying drawings illustrating what I now believe to be the preferred embodiments or mechanical expressions of my invention, from among other forms, constructions, arrangements and combinations within the spirit and scope thereof.

15 The present invention has particular reference to grinding the valves of internal combustion motors. As well known and understood by those familiar with the art, one 20 of the prevailing methods of grinding the valves of an internal combustion motor consists in rotating each valve in and against its seat, a certain amount of pressure being exerted upon the valve, so that the face 25 of the valve bearing and rotated against the face of the valve seat grinds these contacting surfaces away and results in the proper 30 tight seating of the valve. Experience has shown that the most efficient manner of 35 grinding a valve in the above manner is to alternately rotate the same back and forth, approximately a half turn in one direction and a half turn in the reverse direction, at 40 the same time giving the valve a slower rotation, so that the grinding action will be evenly distributed around the contacting surfaces and the valve will seat in proper fit and alinement.

45 One of the objects of this invention is to provide a manually operated grinding tool for carrying out the above mentioned general method of grinding the valves of internal combustion motors, and to so construct and arrange the tool that a valve can be 50 given the slower rotation; these movements being obtained with the expenditure of a minimum amount of movement by an operator and causing an increase in the speed and 55 accuracy of operation with a resulting decrease in time required to properly grind a valve.

Another object of the invention is to provide a grinding tool of the type referred to, in which the rapid back and forth rotation of the valve is imparted by the movement 60 of fingers of one hand of an operator, and the slow rotation of the valve, the pressure is applied to the valve, and the tool is guided and maintained in alinement, by the other hand of the operator. 65

Another object of the invention is to provide a grinding tool of the general type referred to, in which the actuating lever for imparting the rapid, back and forth rotation of the valve, is so constructed, mounted 70 and arranged that it can be positioned between fingers of a hand of an operator and rapidly oscillated by comparatively slight movement of the fingers to secure the desired rotation back and forth of the valve, 75 and without requiring any movement of the operator's arm, thus avoiding the fatiguing effect of arm movement.

Another object of the invention is to provide a grinding tool, of the general type 80 referred to, with an actuating lever adapted to be operated by comparatively slight movement of fingers of a hand of an operator to impart the desired rapid back and forth rotation to a valve, and to construct and 85 arrange this lever so that it provides a stop to limit the range of movement that may be given it by the operator's fingers.

Another object of the invention is to provide an improved guiding and alining handle for a grinding tool of the general type 90 referred to, which handle is adapted to be grasped by a hand of an operator, in such a manner that pressure is exerted on the valve through the palm of the hand, the 95 tool is guided and alined by the fingers of the hand, and the slow rotation is imparted to the valve by movement of the hand grasping this handle.

Another object of the invention is to provide a manually operated valve grinding tool of the general type referred to, in which the energy and extent of manual movement required to operate the same is reduced to a minimum, the speed and efficiency of operation are materially increased and the time required to grind a valve is materially decreased over existing forms of this general type. 100

Another object of the invention is the provision of certain improvements in the arrangement and mounting of the operating 110

gears and the mechanism actuated thereby, as well as to provide improvements in the details of construction and manner of assembling the various elements of a tool embodying the features of the present invention.

With these and other objects in view, my invention consists in certain novel features in constructions and arrangements of parts 10 as more fully and particularly set forth and specified hereinafter.

Referring to the accompanying drawings:

Fig. 1 is a perspective view of a grinding tool embodying the features of the present 15 invention and showing (in dotted lines) particularly the position and relation of the fingers and hands with respect to the operating handles of the tool in grinding a valve (shown in dotted lines).

Fig. 2 is a side elevation showing the operating handle providing a stop limiting the range of movement thereof, parts of the tool being shown in vertical section and parts being broken away.

Fig. 3 is a side elevation showing the tool in a position the reverse of Fig. 2.

Fig. 4 is a detail horizontal section taken on the line 4—4, Fig. 2.

In the particular form and embodiment 30 of the invention illustrated in the drawings, a one-piece body is provided which comprises a centrally open, in this instance, substantially circular, frame 1, a guiding and pressure handle 2, integral therewith and 35 extending laterally and outwardly therefrom, and elongated bearing or journal 3, integral with the frame 1 and extending laterally and outwardly from the frame 1 at a point diametrically opposite and in line 40 with the guiding handle 2. The bearing 3 is formed with a central bore 3^a extending therethrough and in alignment with the longitudinal center of the handle 2. A bushing 3^b of steel or any other desired or 45 suitable material is inserted in and extends throughout the bore 3^a of the bearing 3. The guiding handle 2 terminates in a cylindrical cross bar 2^a, in this instance formed integral with the body length of the handle 2. This head or cross bar 2^a of the handle 2 is formed to fit and be received in the palm of a hand of an operator, as will be 50 fully referred to and explained hereinafter. The inner end portion of the handle 2 is 55 formed with a laterally extending boss 2^b and a bore is provided extending centrally through the boss 2^b and transversely through the handle 2. A shaft 4 is mounted in the bore of the handle 2 and extends 60 through the boss 2^b and a distance therebeyond. The opposite end of the shaft 4 is screw threaded and provided with a nut or the like, 4^a for securing the shaft in the bore of the handle 2. The bearing 3 is provided 65 with an integral raised portion 3^c having a

flat outer face located on the same side of the frame as the boss 2^b and the extended free end of the shaft 4.

A spindle 6 is rotatably mounted in the bearing 3, being suitably journaled in the bore 3^a provided with the bushing 3^b, as clearly shown in Fig. 2 of the drawings. The spindle 6 is formed with a collar 6^a in this instance integral therewith, which abuts against the outer end of the bearing 3 to 75 prevent inward movement of the spindle through the bearing 3. The outer end of the spindle 6 extends a distance beyond the collar 6^a and is suitably screw threaded for interchangeably attaching the grinding bits. The inner end of the spindle 6 extends a distance within the open frame 1 and has a pinion 7 suitably keyed thereon. The pinion 7 is secured against longitudinal movement by a nut 8 on the inner end of the spindle which is screw threaded to receive the same. A flat bearing surface 1^a is formed in the frame 1, around the inner end of the bore 3^a which receives and against which the hub 7^a of the pinion 7 bears.

A segmental gear 9 is rockably mounted on the free end of the shaft 4 and is maintained against displacement therefrom by the enlarged head 4^b of the shaft 4, it being understood of course, that a nut may be utilized in place of the enlarged head 4^b. A washer 4^c is interposed between the head 4^b and the gear 9. The teeth 9^a of the gear 9 are arranged along the inner face adjacent the curved edge thereof and with the gear 9 in position on the shaft 4 are in mesh with the pinion 7 within the frame 1, the diameter of the pinion being greater than the width of the frame and the boss 2^b spacing the gear 9 a distance outwardly from the frame 1. This rocking movement of the gear 9 will impart a back and forth rotation to the pinion 7 and spindle 6. A guard 10 comprising a flat strip of material is secured by screws 10^a or the like, to the flat face of the raised portion 3^c on the bearing 3. The flat strip forming the guard 10 extends a distance inwardly over the outer face of the gear 9 and is bent outwardly so as not to normally contact with the gear but to provide against the gear 9 moving out of mesh with the pinion 7. The guard 10 further provides a stop against which the lug 9^b formed integral with an outer end of the gear 9, abuts and limits the extent of rocking movement in one direction, of the segmental gear 9.

It will be noted that the segmental gear 9 is formed with the straight radial edges 9^c and 9^d extending from the center upon which the gear is rocked, at which point the gear 9 is mounted upon the shaft 4, to the curved outer edge thereof at an acute angle to the center line dividing the segmental gear. Along the inner face of the segmental gear 130

9 and parallel to the edge 9^d are a pair of parallel, spaced ribs 11, in this instance, formed integral with the body of the gear 9. An operating handle 12 formed of a flat 5 strip of steel, or any other suitable material, is secured at its inner end between the ribs 11 and against the face of the gear 9 by rivets, bolts or the like 13.

This flat strip handle 12 extends outwardly 10 a distance beyond the gear 9 and parallel and in line with the straight edge 9^d of the gear 9. The extended free length of the handle 12 is twisted until the plane of the strip forming the same lies at right angles to 15 the plane of the portion secured between the ribs 11 and against the inner face of the gear 9. The twisted or bent portion 14 of the handle 12 is located at the edge of the gear 9 and provides a shoulder 14^a which 20 forms a stop to abut against the edge of the frame 1 to limit downward rocking of the handle 12 and gear 9.

The outer end of the spindle 6 is screw threaded and a grinding bit 15 having a 25 longitudinal screw threaded bore 15^a is screwed thereonto.

A lock nut 15^b is mounted on the spindle 6 and is adapted to lock the bit 15 in the desired position on the spindle. The particular grinding bit illustrated is of the 30 screw driver type and adapted for use with grooved valves. It is to be understood, of course, that various types and forms of bits may be utilized and are formed to interchangeably fit the spindle 6, for use with 35 various valves.

Referring particularly to Figure 1 of the accompanying drawings, in operation the bit 15 is placed in the groove of the valve V 40 shown in dotted lines, and the hand L of an operator is placed over the handle 2 with the palm resting upon the cross bar 2^a and the fingers 1 of the hand bearing lightly against the opposite sides of the body length of the handle 2. The desired pressure is applied to 45 the valve through the hand L and the fingers 1 are utilized to align and guide the tool. The operator then engages the flat handle 12 with the opposite hand R, the handle being held between the fingers r¹ and r², preferably the so-called first and second fingers of a hand. It is seen that the flat sides of the handle 12 are engaged by the 50 fingers r¹ and r² and hence these are not to any appreciable degree separated but remain in normal and natural extended position. Now, by an entirely finger and hand 55 movement and without bringing the arm of the operator into play, the fingers r¹ and r² are rapidly moved up and down in what might be termed a "jiggling" movement. This up and down movement rocks the gear 9 and 60 through pinion 7 causes an alternate back and forth rotation of the spindle 6 and the 65 valve V, which bears against its seat (not

shown) and grinds away the contacting surfaces. Simultaneously with the rapid up and down movement of the fingers of the hand R, a slow rotation is imparted to the entire tool by the hand L through the handle 2 and cross bar 2^a in this manner causing slow rotation of the valve V to apply the back and forth grinding rotation evenly around the valve and its seat. As hereinbefore explained, the most efficient and rapid 70 method of grinding valves in the manner described is to impart the rapid back and forth rotation about a half turn in each direction. Due to the construction and arrangement of the operating handle 12 and the gear 9, 75 this half turn, alternate rotation is readily imparted to the valve by the finger motion and with greater accuracy and speed than heretofore possible where an arm movement has been required to operate the tool. 80

The natural limits of the up and down movements of the fingers of a hand in imparting the "jiggling" movement to the handle 12 in position therebetween, is such that, the gear 9 is rocked a distance to rotate the 90 spindle and the attached bit the half turn in each direction within quite an accurate degree and without other care and attention on the part of the operator than to maintain the finger movement within the natural limits defined by the beginning of an arm movement when exceeded. The operator can remain within these natural limits of movement very readily and without giving any special thought or attention thereto, thus 95 permitting very rapid movement with substantial accuracy in the valve rotations and a very appreciable increase in speed of the operation.

The peculiar flat form and construction of the handle 12 with the twist 14 provides the shoulder 14^a adapted to strike or abut against the frame 1 to form the extreme limit of downward movement, while the lug 9^b at the opposite end of the gear 9 provides 100 the stop adapted to strike against the guard 10 and form the extreme limit of upward movement of the gear 9, in operation. The body of the tool consisting of the handle 2—2^a, the frame 1 and the elongated bearing 115 3 formed in one piece provides for easy and inexpensive manufacture and presenting an extremely simple but strong construction. The handle 12, being preferably formed of steel adds to the strength of the tool in that 120 it will not be readily broken in the operation and hard usage to which these grinding tools are put in use. The simplicity of the bearing constructions which receive the moving surfaces and the general arrangement 125 and assembly provides a grinding tool of this type which is extremely simple but durable and which permits of increased accuracy and production due to the hereinbefore described mode of finger operation. 130

It is evident that various changes, modifications and variations might be resorted to without departing from the spirit and scope of my invention and hence I do not wish to limit myself to the exact disclosures hereof.

What I claim is:—

1. In a valve grinding tool, the combination with a frame, a spindle journaled in the frame, a pinion mounted on said spindle, and a rockably mounted segmental gear in mesh with said pinion for imparting a back and forth rotation to said spindle, of, a flat operating handle secured to said gear and extending radially a distance therefrom, the extended length of said handle twisted longitudinally at approximately a right angle to the secured length and the twisted portion of said handle forming a shoulder adapted to engage said frame to limit movement of said handle, gear and spindle.
2. In a valve grinding tool of the type described, the combination with a frame, a guiding and pressure handle therefor, a spindle rotatably journaled in said frame opposite and in line with the said spindle, and a segmental gear rockably mounted in

mesh with said pinion for imparting an alternate back and forth rotation of approximately half a turn in each direction to the said spindle, of, an operating handle consisting essentially of a comparatively narrow flat strip secured to the inner face of the said gear adjacent and parallel to one of the radial edges thereof and extending a distance outwardly therefrom, the extended length of said handle longitudinally twisted with the flat faces thereof at approximately right angles to the secured flat faces and the twisted portion forming a stop to engage the adjacent outer edge of the frame and limit 30 rocking movement of the said handle and gear, the form and arrangement of the operating handle being such that it is engaged between normally extended fingers of the hand of an operator and rapidly rocked 35 within the natural limits of extended finger movement whereby a rapid back and forth rotation of half a turn in each direction is imparted to said spindle, substantially as shown and described.

THEODORE A. PARMENTER.
